UNITED STATES PATENT OFFICE.

NELS J. BENSON, OF GENEVA, IOWA.

DEVICE FOR COOLING GAS ENGINES.

Application filed May 2, 1927. Serial No. 188,312.

The present invention is directed to improvements in devices for cooling gas engines.

The primary object of the invention is to provide a device of this character so constructed that air will be pumped into the water jacket of the engine in order that the water will be maintained in a cool state by the incoming air which will also cause the water to circulate.

Another object of the invention is to provide a device of this kind which will eliminate the usual cooling fan.

Still another object of the invention is to utilize the air for conducting moisture to the intake manifold of the engine for mixture with the fuel to aid in the carburetion thereof.

In the accompanying drawings:

Figure 1 is a side view of an engine, showing the device in place thereon.

Figure 2 is a top plan view of the same.

Figure 3 is a partial vertical sectional view through one of the engine cylinders.

Figure 4 is a front view of the air pumps and their driving connections.

Figure 5 is a fragmentary perspective view of the air manifold.

Referring to the drawings, 1 designates a gas engine, 2 the radiator and 3 the fan driving shaft, the engine being equipped with the usual jacket 4 providing the water space 5, as customary.

Suitably mounted adjacent the radiator 2 is a pair of air pumps 6, which have the lower ends of their piston rods 7 pivotally connected to the ends of the beam 8, said beam being pivotally connected intermediate its ends to a bracket 9 which may be secured to the engine base in any desired manner.

A disk 10 is fixed to the shaft 3 in lieu of the usual fan and has pivoted eccentrically thereto the upper end of the pitman 11, the lower end of which is pivotally connected to the beam 8 upon one side of its pivotal connection with the bracket 9. The shaft 3 is driven from the engine shaft by the usual belt 12.

Mounted in the space 5 upon opposite sides of the cylinders 13 are manifolds 14 having perforations 15 formed therein, each mani-

fold having extending therefrom branches 16, preferably four in number, said branches being provided with perforations 17. Leading from each pump cylinder 6 is an air conducting pipe 18 which connects with the respective manifolds in order that air from the pumps will be discharged into the manifolds and their branches. A pipe 19 is lead from one of the pipes 18 and connects with the crank case 20 in order that air will enter the crank case to cool the air therein, this pipe being preferably extended to the breather pipe 21.

A pipe 22 is provided and has one end fitted to the radiator cap 23 and its other end fitted to the intake manifold 24 in order to conduct moist air from the radiator into said intake manifold.

It will be obvious that when the engine is in motion that the shaft 3 will impart rotary motion to the disk 10 through the medium of the pitman 11 the beam 8 will be rocked, thus reciprocating the pistons 25 in the cylinder 6. Air compressed by the pistons upon the up stroke will be forced from the cylinders through the pipes 18 and into the respective manifolds 14 and branches 16. The air passing from the perforations of the manifolds and branches will not only cool the water in the space 5 but will also aid in circulating the water therein.

Having thus described the invention, I claim:

1. In combination with a gas engine, air pumps operable by the engine, manifolds in the water jacket of the engine and having branches carried thereby, and means for conducting air from the pumps into the manifold and branches for discharge from the branches into the water jacket.

2. In combination with a gas engine and its fan shaft, a disk fixed to the fan shaft, pumps associated with the engine, a beam, a pitman connecting the beam and disk, pistons in the pumps, rods for the pistons having pivotal connection with the beam, and means for conducting air from the pumps to the water jacket of the engine during operation of the beam.

In testimony whereof I affix my signature.

NELS J. BENSON.
